UNITED STATES PATENT OFFICE.

LAWRENCE J. WALSH, OF BROOKLYN, NEW YORK.

AUXILIARY DOOR.

Application filed May 26, 1928. Serial No. 280,678.

My invention is known as an auxiliary door and relates to devices attached to an entrance door or the door of a room so that the small auxiliary door or aperture may be 5 opened first in order to ascertain the purpose of the person desiring to enter.

The objects of the invention are to protect or guard the home or the premises from the intrusion of persons who could easily 10 gain entrance by force or otherwise once the main door was opened for any reason. This protection and the privacy afforded thereby is highly desirable not only in private homes but also in apartments, hotel 15 rooms, staterooms on steamships, compartments on trains, bath rooms and private offices, etc.

The objects are attained by the installation of the auxiliary door in a suitable position in the door, preferably in the center of the door at a height about level with the eyes of the average adult person. When one approaches the door from without and rings the bell or knocks on the door for admittance, the occupant instead of opening the room door forthwith, open the auxiliary door and by this means is able to see and talk with the caller and ascertain the purpose of the person before admitting him to the premises.

The foregoing objects are obtained by the means illustrated in the accompanying drawings, in which merely the preferred form of my invention is shown and in which—

Figure 1 is a perspective view from the inside of a room showing my invention installed in a door, the door of the room being closed and the auxiliary door opened.

Figure 2 is a transverse section of the device as attached to a thick door (such as an outside door) and illustrates the method of attaching same, the outside closure member, the inside member for covering opening or aperture in the outside member and the ring (required on thick doors) on the inside of the door against which ring the flange in the inside of the closure member closes tightly so as to cover up the hole made in the door. The dotted lines indicate

the positions taken as the inside closure member is opened.

Figure 3 is a transverse section of the device, such as used on a thin panel door, and shows the inside member open illustrating 55 the operation of the hinge-post.

Figure 4 is a plan view of auxiliary door in which the relation of the various parts is disclosed. It is partly broken away to show the packing ring, the recess for the packing, the vertical section of the closure member, the re-inforcing web member, the neck section of knob or handle, the integral key in knob section, the cross-section of operating shaft, the key-way in the shaft, the top screw hole in center of shaft, the hinge-leaf, the stop projection bearing against latter, and the hinge-post.

Figure 5 is a transverse section on the line 2—2 of Fig. 4, and shows the interior construction when the device is closed, the hinge-post, the manner in which the flange of the auxiliary door is forced against the lugs and the packing ring when the device is closed, thereby making a water-tight 75 joint. This view also shows the device as attached to a very thin door panel.

Figure 6 is a side elevation of the hinge-post, partly in section, showing the adjustment holes which are used to adjust the device for use in doors of varying thickness, also showing the bearing sleeves with trunnions integral therewith making a flexible connection for attaching the hinge-leaf. The method of attaching the hinge-leaf is 85 shown in the part broken away.

Figures 7 and 8 are section views showing, in part, the detail of lugs on the outside member and the inside member, the introduction of the edge of the male lug into the female lug and the bearing of same against the tapered edge of the female lug, thereby causing pressure against the flange of the inside member and in turn against the packing ring causing a water-tight joint.

The same reference characters indicate the same parts in all the drawings.

Referring to the drawings the safe-guard auxiliary door is installed and functions as follows:

A hole of suitable size is cut in the door A. (Fig. 1) to admit the insertion of the auxiliary door B, which speaking generally, consists of three principal parts, the outside member or ring 1 containing an aperture 2 to look through, the inside of closure member 3 and in the case of a thick door, an inside ring 4 used to cover the hole made in the door.

10 Referring to Fig. 2 the outside ring or flange portion 1 bears evenly and smoothly at every point without strain. On the inside of the flange member 1 and integral therewith are four or any suitable number of 15 bosses 5 with concentric holes 6 threaded internally for screws 7 (of which there are usually four) which latter are for the purpose of holding the outside member 1 firmly against the door, the top of screws 7 resting against the inside ring 4. The outside member 1, the packing ring 11, the bosses 5, the lugs 10 and the hinge-posts 12 are cast integral.

20 The inside member 3 fits even with the outside face of the part 1, thereby closing up the ring or aperture 2 on the outside of the door while near the top of the handle 8 is an inside flange 9 used to cover the hole on the inside of the door. The inside flange 9 in turn sets against a separate ring 4 attached to the inside of the door thereby closing the hole on the inside of the door and giving a proper finish to same.

25 Having described the main elements of the device the detailed construction will now be set forth:

30 The outside flange 1 consists of a ring which is smooth on the outside and on the inside are bosses 5 (usually four in number) 40 clamping lugs 10, a recessed packing ring 11, two hinge-posts 12, and a shaft 14, all of which are cast integral with the flange 1.

35 The inside or closure member consists of a round disk 3 having a stop projection 13 (see Fig. 4) set near the periphery of the disk 3, and in the center of the disk and integral therewith, is a shaft 14 with a keyway 15, at the upper end of the shaft 14 is attached a knob or handle 8 in which there 45 is a key 19 cast integral with knob on inside bore. The knob 8 contains a screw 20 which attaches the knob to the shaft 14. The shaft 14 is threaded at 21 internally for a considerable distance so as to make the shaft 14 50 adjustable to doors of varying thickness. In the case, as in Fig. 2, where the device is applied to a thick door the inside flange 9 is adjusted and held against the shaft 14 by a set-screw 22.

60 The hinge member of the device consists of two principal parts, a sliding bearing 23 and a hinge-leaf 24. The hinge-leaf 24 containing a hole or bore 25 of proper size to fit closely around the shaft 14, the same be-

ing held in place on shaft by means of a pin 65 26.

The hinge-leaf 24 is made to conform to the circular disk 3 and is approximately the same size, the purpose of the large surface of the leaf is to provide a suitable bearing 70 surface on the disk 3 to hold this member in alignment with the aperture 2.

Eccentric to the bore 25 in hinge-leaf 24 is a curved slot 27 which coincides with the stop projection 13 for purposes of stopping 75 rotation of the disk 3 so as to either mesh or unmash lugs 29 and 10. The sliding bearing 23 has two trunnions 28 integral therewith over which the hinge-leaf 24 is fitted. There are two hinge-posts 12 which, as stated, are cast integral with the outside member 1, and the posts contain a plurality of adjustment holes 35 and at a suitable distance (depending upon the thickness of the door) there is inserted a stop-pin 34 85 which permits the sleeve slide 23 and the hinge-leaf 24 to travel to the extreme end of hinge-post 12 so as to allow for the clearance of the disk 3. The sleeve-slide 23 and the hinge-pins or trunnions 28 are made integral.

90 On Fig. 4, shown as 24^a, integral with hinge-leaf are shown two (2) shoulders the purpose of which is to keep the disk 3 parallel with aperture 2 from top of, and at right angles with hinge posts 12 all the way down to contact ring or ridge 32 with packing ring 11, thus assuring an easy, smooth entry of bottom portion of closure member 3 into aperture 2 without interference.

95 Shoulders, or guides 24^a normally bear against sleeve bearings or travelers 23 on hinge-posts 12 except at incident of turning over top of hinge-posts 12, as shown in detail, in Fig. 6.

100 Important features of the invention are the male lugs 29 and female lugs 10 for clamping which are shown in further detail in Figs. 5, 7 and 8. The female lug 10 which is part of the flange 1 has a matched 110 taper surface or projection 30 which coincides with matched taper surface 31, in male piece 29 in disk 3 and these tapered parts when brought together in mesh exert pressure on disk 3 which in turn forces contact 115 ring 32 of disk 3 to yielding surface of packing ring 11 in recess of flange 1. On top surface of female lug 10 is provided a ramp 33 of suitable pitch which, if and when male lug 29 is brought down against ramp because of the pitch provided on the ramp the lug 29 and consequently the disk 3 will 120 gravitate or slide to the positions indicated in Figs. 7 and 8 and thence, by turning the knob 8 slightly the male and female portions of lugs are brought together thus effecting a water-tight joint at the contact point 32 of the disk in connection with the pack-

ing ring 11. The various positions taken by the male lug 29 when going into the female lug 10 are indicated in Figs. 7 and 8.

The disk 3 is turned or rotated slightly 5 to left thereby clearing the male lugs 29 from the female lugs 10 after which the disk 3 can be withdrawn from the aperture 2 because the hinge-leaf 24 is pulled along the hinge-posts 12 until it reaches the extreme end thereof where it is stopped by the stop pins 34 provided at this point, the handle 8 is then pulled to the right thereby turning the hinge-leaf 24 and the disk 3 at right angles to the hinge-posts 12, after 10 which the aperture 2 is entirely open for the purpose of observation and conversation with the person outside the door. To close the aperture, the procedure is reversed and when the lugs 29 strike the ramp 33 they 15 slide off until they fall below same and the shaft 14 is slightly rotated by means of the handle 8 until the lugs mesh which, as before stated, causes a water-tight joint.

Having thus described my invention, I 20 claim as new:

1. An auxiliary door so arranged that it 25 may be inserted in the panel of a door, the said device being constructed of metal and consisting of an exterior member having an aperture to be applied to the outside of a door and an interior closure member or disk applied on the inside so that the outside surface of the said disk is flush with the exterior member when the device is closed 30 and a rotatable shaft cast integral with said disk, a hinge-leaf attached at one point to the shaft and at the other end to hinge-posts by means of sliding sleeves and trunnions, thereby providing means for opening the 35 inside member parallel to the aperture so that one may look through the opening made by the auxiliary door.

2. An auxiliary door so arranged that it 40 may be inserted in the panel of a door of any kind, the said device consisting of an exterior member having an aperture to be applied to the outside of a door and an interior closure member applied on the inside so that the outside surface of the said member is flush with the exterior member when device is closed and a rotatable shaft cast integral with said member, a hinge-leaf attached 45 at one point to the rotatable shaft and at the other end to hinge-posts, sliding sleeves and trunnions, thereby providing means for opening the inside member so that the one may look through the opening made by the auxiliary door, the said hinge-posts and sliding sleeves and trunnions making it possible for closure member to clear the sides of the aperture in the door while opening or closing 50 same, said hinge-posts having a plurality of holes at suitable intervals which may be used for purpose of adjusting device to fit doors of varying thickness and said hinge leaf so attached to the rotatable shaft that the closure member or disk may be swivelled on said hinge-leaf to either side by the said hinge leaf operating against a limiting stop on the said closure disk so as to confine the 55 swivel action of same to predetermined limits thereof.

5. An auxiliary door so arranged that it 60 may be inserted in the panel of a door of any kind, the said device consisting of an exterior member having an aperture to be applied to the outside of a door and an interior closure member applied on the inside so that the outside surface of the said disk is flush with the exterior member when device is closed and a rotatable shaft cast integral with said member, a hinge-leaf attached 65 at one point to the rotatable shaft and at the other end to hinge-posts with sliding sleeves and trunnions, thereby providing

any kind, the said device consisting of an exterior member having an aperture to be applied to the outside of a door and an interior closure member applied on the inside so that the outside surface of the said member is flush with the exterior member when device is closed and a rotatable shaft cast integral with said member, a hinge-leaf attached at one point to the rotatable shaft and at the other end to hinge-posts, sliding sleeves and trunnions, thereby providing means for opening the inside member so that one may look through the opening made by the auxiliary door, the said hinge-posts and sliding sleeves and trunnions making it possible for closure member to clear the sides of the aperture in the door while opening or closing same, and said hinge-posts having a plurality of holes at suitable intervals which may be used for purpose of adjusting device to fit doors of varying thickness.

4. An auxiliary door so arranged that it 70 may be inserted in the panel of a door of any kind, the said device consisting of an exterior member having an aperture to be applied to the outside of a door and an interior closure member applied on the inside so that the outside surface of the said member is flush with the exterior member when device 75 is closed and a rotatable shaft cast integral with said member, a hinge-leaf attached at one point to the rotatable shaft and at the other end to hinge-posts with sliding sleeves and trunnions, thereby providing means for opening the inside member so that one may look through the opening made by the auxiliary door, the said hinge-posts and sliding sleeves and trunnions making it possible for closure member to clear the sides of the aperture in the door while opening or closing 80 same, said hinge-posts having a plurality of holes at suitable intervals which may be used for purpose of adjusting device to fit doors of varying thickness.

5. An auxiliary door so arranged that it 85 may be inserted in the panel of a door of any kind, the said device consisting of an exterior member having an aperture to be applied to the outside of a door and an interior closure member applied on the inside so that the outside surface of the said disk is flush with the exterior member when device is closed and a rotatable shaft cast integral with said member, a hinge-leaf attached 90 at one point to the rotatable shaft and at the other end to hinge-posts, sliding sleeves and trunnions, thereby providing means for opening the inside member so that one may look through the opening made by the auxiliary door, the said hinge-posts and sliding sleeves and trunnions making it possible for closure member to clear the sides of the aperture in the door while opening or closing 95 same, said hinge-posts having a plurality of holes at suitable intervals which may be used for purpose of adjusting device to fit doors of varying thickness and said hinge leaf so attached to the rotatable shaft that the closure member or disk may be swivelled on said hinge-leaf to either side by the said hinge leaf operating against a limiting stop on the said closure disk so as to confine the 100 swivel action of same to predetermined limits thereof.

5. An auxiliary door so arranged that it 105 may be inserted in the panel of a door of any kind, the said device consisting of an exterior member having an aperture to be applied to the outside of a door and an interior closure member applied on the inside so that the outside surface of the said disk is flush with the exterior member when device is closed and a rotatable shaft cast integral with said member, a hinge-leaf attached 110 at one point to the rotatable shaft and at the other end to hinge-posts with sliding sleeves and trunnions, thereby providing

means for opening the inside member so that one may look through the opening made by the auxiliary door, the said hinge-posts and sliding sleeves and trunnions making it possible for closure member to clear the sides of the aperture in the door while opening or closing same, said hinge posts having a plurality of holes at suitable intervals which may be used for purposes of adjusting said device to fit doors of varying thickness, said hinge leaf so attached to the rotatable shaft that the closure member or disk may be swivelled on said hinge-leaf to either side by the said hinge-leaf operating against a limiting stop on the said closure disk so as to confine the swivel action of same to predetermined limits thereof, and male and female cams or lugs, integral with the inside and outside closure members respectively, so arranged that when same are brought together in mesh the opening in the device is locked and when male lugs are rotated by means of shaft the device may be opened.

6. An auxiliary door so arranged that it may be inserted in the panel of a door of any kind, the said device consisting of an exterior member having an aperture to be applied to the outside of a door and an interior closure member applied on the inside so that the outside surface of the said member is flush with the exterior member when said device is closed and a rotatable shaft cast integral with said disk, a hinge-leaf attached at one point to the rotatable shaft and at the other end to hinge-posts, sliding sleeves and trunnions, thereby providing means for opening the inside member so that one may look through the opening made by the auxiliary door, the said hinge-posts and sliding sleeves and trunnions making it possible for closure member to clear the sides of the aperture in the door while opening or closing same, said hinge posts having a plurality of holes at suitable intervals which may be used for purposes of adjusting said device to fit doors of varying thickness, said hinge leaf so attached to the rotatable shaft that the closure member may be swivelled on said hinge-leaf to either side by the said hinge-leaf operating against a limiting stop on the said closure member so as to confine the swivel action of same to predetermined limits thereof, male and female cams or lugs, integral with inside and outside closure members respectively, so arranged that when same are brought together in mesh the opening in the device is locked and when male lugs are rotated by means of shaft the device may be opened, and the said male and female lugs having tapered surfaces, wedge-shaped and opposed to one another so that when same are drawn together in mesh, pressure is exerted against the closure member or disk thereby forcing a contact bead or edge on disk into a recessed groove containing a

packing ring, thus making a water-tight joint, as shown.

7. An auxiliary door so arranged that it may be inserted in the panel of doors of varying thickness, the said device having an outside member shaped like a ring, with a recessed packing ring, two hinge-posts, female lugs and bosses threaded internally for attaching said device by screws on the inside of door, all of which are cast integral; 75 an inside closure member fitting in and flush with said outside member when closed, means for opening said member consisting of a rotatable shaft and a limiting stop cast integral therewith, a hinge-leaf attached to said rotatable shaft at one point and to hinge-posts by means of sleeve-bearings at the other end, said hinge-leaf being held close against the closure disk by a pin in said shaft and the rotation of the shaft being possible only to the limits prescribed by the limiting stop operating in a slot in the said hinge-leaf, as shown.

8. An auxiliary door so arranged that it may be inserted in the panel of doors of varying thickness, the said device having an outside member shaped like a ring, with a recessed packing ring, two hinge-posts, female lugs and bosses threaded internally for attaching said device by screws on the inside of door, all of which are cast integral; 90 an inside closure member fitting in and flush with said outside member when closed, means for opening said member consisting of a rotatable shaft and a limiting stop cast integral therewith, a hinge-leaf attached to said rotatable shaft at one point and to hinge-posts by means of the sleeve-bearings at the other end, said hinge-leaf being held close against the closure disk by a pin in said shaft and the rotation of the shaft being possible only to the limits prescribed by the limiting stop operating in a slot in the said hinge-leaf and suitable flanges for inside of door, the same consisting of an 100 inside ring to go around hole in door and a circular flange attached to the neck of the shaft by a set screw for purpose of covering inside of device and to provide a suitable finish for the interior of the door, substantially as shown.

9. An auxiliary door so arranged that it may be inserted in the panel of a door of any kind, the said device being adjustable to fit the thickness of the door and consisting of an exterior member closely fitting the outside panel of the door and having a hole therein for purposes of observation, hinge-posts cast integral with the exterior member and a part operating on said hinge-joint so as to provide an opening through which may be seen those desiring to enter the premises; said exterior member provided with a packing ring, bosses and lugs, the said packing being positioned in a re-130

cessed portion of said exterior member thereby providing a water-tight joint; an interior member operated by turning same by means of an adjustable knob which when turned about a quarter turn releases a flange on said interior member from the lugs on the exterior member and permits the opening of a port through which the person desiring admission to the premises may be inter-

viewed, said posts having a plurality of 10 holes for adjusting the auxiliary door to the thickness of any door and two sliding-sleeves cast integral with trunnions supporting a hinge-leaf used in the opening and closing of the port, substantially as shown. 15

In witness whereof, I have hereunto set my hand.

LAWRENCE J. WALSH.
